DESIGN FOR A DRESS

Marie Mascitelli, New York, N. Y.

Application September 30, 1938, Serial No. 80,152

Term of patent 3½ years

To all whom it may concern:

Be it known that I, Marie Mascitelli, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein—

The characteristic feature of my design resides in the combination on the dress disclosed of the specific bead embroidery on the blouse section as shown.

I claim:

The ornamental design for a dress, substantially as shown and described.

MARIE MASCITELLI.
